Inventor

UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

CENTRIFUGAL FIXTURE.

Application filed November 28, 1924. Serial No. 752,722.

In operating steam boilers and in like processes of evaporation and distillation, it is assumed and desired that the steam or other vapor evolved shall leave the steam or vapor drum in a pure state, that is free from globules of liquid and particles of solid matter. As a rule the conditions controlling and modifying the operation in at least some measure defeat this primary expectation of purpose with the result that the vapor leaves the drum in an impure state. The present invention comprises a centrifugal fixture; that is, a device that does not itself move or rotate, but nevertheless 15 reliably induces a strong centrifugal action within the stream or streams of escaping steam or other fluid evolved, whereby the foreign substances are removed from the fluid to be later returned to the body of liquid undergoing evaporation or discharged externally if it is desired to rid the boiler or evaporator of such substances. The most difficult cases for consideration doubtless are presented by steam boilers having steam drums partly occupied by steam and partly by boiler water in a state of violent agitation. In some boilers the agitation is greatest at the middle portion of the drum; in others the agitation is largely located at 20 one end of the drum. Not infrequently the boiler nozzles or outlets must be located quite directly opposite the points of more violent agitation within the steam drums, and such cases present the greatest difficulties when it is attempted to purify or dry the steam leaving the steam drums. This invention has for its special object the mastering of the particular difficulties above presented. To this end my invention comprises a steam drum or the like having an outlet or nozzle in its top and equipped with a reach tube within the drum and extending from its nozzle toward the end of the drum where the agitation of the liquid is likely to be least. And at that point the reach tube is equipped with a centrifugal separator or fixture, through which the steam or other vapor enters the reach tube. As will presently appear, the fixture is of 25 such construction that the entering steam is caused to whirl violently as a preliminary to entering the reach tube and just prior to such escape of the vapor it is deprived of its burden of liquid globules and solids,

the latter being separated from the vapor by the centrifugal forces developed in the whirling of the outgoing vapor.

Further objects and details of the invention will appear hereinafter.

The invention will be readily understood on reference to the drawings that form part of this specification and in which:—

Fig. 1 is a vertical longitudinal section of a steam boiler drum containing a centrifugal fixture embodying my invention. Fig. 2 is a similar view illustrating a drum having its outlet or nozzle at one end and the centrifugal fixture at the other. Fig. 3 is a cross-section showing the position of the parts in the steam drum. Fig. 4 is an enlarged longitudinal cross-section of one of the centrifugal fixtures proper. Fig. 5 is an end view of the fixture partly in section on the line 5—5 of Fig. 4. Fig. 6 is a cross-section on the line 6—6 of Fig. 4, viewed in the direction of the arrow 6. Fig. 7 is a cross-section on the line 6—6 of Fig. 4 viewed in the direction of the arrow 7, and incidentally shows tuyère blades of modified shape, and Fig. 8 is an enlarged cross-section on the line 5—5 of Fig. 4 intended to better illustrate the drain in the bottom of the horizontally positioned centrifugal fixture.

In Figs. 1, 2 and 3 the steam drum is marked 1. As usual, the drum is characterized by a manhole 2 and cover plate 3 at one end. As is usual with the uppermost drum of a steam boiler, the top of the drum serves as the steam space 4, while the lower part of the drum is filled with boiler water 5. The disengagement surfaces are marked 6.

The drum of Fig. 1 has its steam outlet or nozzle 7 in its top and midway between its ends. This may be assumed to represent the drum of a water-tube boiler, the tubes of which (not shown) directly enter the bottom of the drum. In such cases a very irregular disengagement of surface is presented, the boiler water tending to the most violent agitation and rising to the greatest height at the middle of the drum. A contrasting case is presented in Fig. 2, which is assumed to represent the steam drum of a water-tube boiler of the header type, in which the disengagement agitation is localized at one end of the boiler. Where, as in Fig. 2, the steam outlet nozzle 8 may be located near the front

or most active end of the boiler, it is extremely difficult to prevent the priming of the steam.

Accepting such difficult conditions, my invention comprises in each case a fitting 9 or 9', positioned at the boiler nozzle, and in free communication therewith. Next, a reach tube extending to the quiet end of the drum and finally a centrifugal fixture or separator positioned on the end of the reach tube in the quiet end of the drum. In such cases as presented by Fig. 1 the fitting 9 takes the form of a $\frac{1}{4}$ with two reach tubes 10—10 extending into respective ends of the drum, and each reach tube is equipped with its centrifugal fixture 11. These fixtures and their discharge pipes will be more fully described hereinafter.

In the case of Fig. 2 the fitting 9' takes the form of an elbow and a single reach tube 12 extends therefrom to the opposite end of the drum, where the centrifugal fixture 13 is applied. Obviously only steam of the best quality evolved can find its way to the nozzle, and to do so it must pass through the centrifugal fixture or fixtures and the corresponding reach tubes. There are no perforations in the latter unless perhaps one or more drain plugs 14 be provided for conveniently emptying them of condensation when the boiler is cold.

The preferred form of centrifugal fixture demanded by my invention comprises two main parts, see Figs. 4 to 8. The part marked 15 in the several figures of the drawing is a hollow ring or body portion of little depth. This contains the central outlet opening 16 formed within the collar 17. The latter is peripherally threaded to receive the end of the reach tube and the interior of the latter actually forms the central discharge outlet of the centrifugal fixture. The part 15 contains the circular race 18, which, at one side, is provided with the tangential peripheral discharge nozzle 19. At the bottom the race is also provided with a small drain opening or tuyere 20, to be referred to later. The large opening 21 of the part 15 directly communicates with the interior of the annular tuyere ring 22. The latter is attached to the member 15 as by screws or bolts 23. Its principal members are the bottom or end closure 24 and the annular series of tuyere blade 25. The blades are tangentially positioned and may be either of the overlapping type shown in Fig. 6 or of the nonlapping type shown in Fig. 7. In either case the steam entering through the tangential tuyères 25' (the relatively long and narrow slots between the tuyere blades) is therefore prevented from directly moving

toward the outlet 16 and takes on a rapid whirling motion within the tuyere ring and within the race 18. In consequence of this rotation the globules of moisture and particles of solid matter carried by the steam are centrifugally separated, and, being accumulated in the race 18, are forcibly expelled through the nozzle 19. Thus, the impurities are prevented from entering the reach tube, leaving only the purified steam to pass to the nozzle and thence escape from the boiler. The impurities from the nozzle 19 may be discharged directly back into the boiler, but by preference they are conducted away through a pipe and eventually discharged through an external trap 26. The plural equipment of Fig. 1 requires two such discharge pipes, but these may be joined within the drum so that the combined discharge 80 may pass to a single trap.

Due to the form and position of the parts, water of condensation may accumulate therein when the boiler is shut down. The drains 20 are employed to prevent the accumulation of water of condensation in the race bottoms of the centrifugal fixtures. As clearly shown in Figs. 5 and 8, the drain 20 is constantly open. When the boiler is shut down any accumulation in the race may freely drain therefrom. The drain hole enters the race tangentially so that during the operation of the boiler the steam which naturally enters there-through shall be given the same direction as the whirling substances within the race. In other words, the position of the tuyere 20 is such as to prevent the disturbance of the collected substances by the in-flowing jet of raw steam at the drain 20.

As various modifications of the invention will suggest themselves to those skilled in the art, it is to be understood that this invention is not restricted to the specific disclosures of the drawings, but is coextensive with the appended claim.

Having thus described my invention, I claim as new and desire to secure by Letters Patent:

A centrifugal fluid purifying fixture adapted to operate upon its horizontal axis, comprising an annular race member having a tangential drain opening in its bottom and provided with a tangentially opposed peripheral discharge nozzle, in combination with a multiply tuyèred ring adapted to whirlingly direct fluid into said race member.

In testimony whereof, I have hereunto set my hand this 24th day of November, A. D. 1924.

CHARLES GILBERT HAWLEY.
